UNITED STATES PATENT OFFICE.

FRANCIS A. CHASE, OF JORDAN, NEW YORK.

IMPROVEMENT IN DOUBLE-ACTING HOLLOW-PISTON PUMPS.

Specification forming part of Letters Patent No. 43,637, dated July 26, 1864.

To all whom it may concern:

Be it known that I, FRANCIS A. CHASE, of Jordan, county of Onondaga, and State of New York, have invented a new and Improved Pump; and I do hereby declare that the following is a full, clear, and exact description thereof, reference being had to the accompanying drawings, making a part of this specification, in which—

Figure 1 is a vertical diametrical section through my pump. Fig. 2 is a horizontal section taken through the middle of the pump. Fig. 3 is a side view, a part of which is shown in section to expose the ports. Figs. 4 and 5 represents the double-wing supply-valve and its seats.

Similar letters of reference indicate corresponding parts in the several figures.

This invention relates to certain improvements on that class of pumps having a hollow piston-rod, through which the water is forced by the alternate reciprocating movements of the piston, as will be hereinafter described.

To enable others skilled in the art to make and use my invention, I will describe its construction and operation.

The main portion or body of the pump consists of a cylinder, A, closed at its ends by means of heads B B', and having passages C C' formed on one side, through which latter the water enters the cylinder A. The induction-passages C C' are separated from each other by a central partition, a, between which and the transverse division of the port-box D a double-wing supply-valve, E, is pivoted, as shown clearly in Figs. 1 and 2. The box D is constructed with two openings or ports, b b', through it, communicating with the respective induction-passages C C', and that portion of this box which fits within said passages is ground smoothly in order to form seats for the valve E. This box D is removable—i. e., it is secured in position over the entrance to the passages C C' by means of screw-bolts c c, by the removal of which the box D, together with the double-wing valve E, can be taken off and inspected. The faces of the valve E form an obtuse angle to each other, and at this angle the pin e passes through the connection f of the two wings and pivots them between the lugs g g which project from the transverse division of the box D, as clearly represented in

Figs. 1, 4, and 5. The ports b b', which communicate with the induction-passages C C', will be alternately opened and closed by the wings of the valve E, acting against their respective seats and working within their respective induction-passages, as will be hereinafter further explained.

The piston-rod F, which is hollow, passes through the head B of the pump-cylinder, and has a circular disk, G, suitably secured on its end, as shown in Figs. 1 and 2. The diameter of this disk G is somewhat less than that of the cylinder within which it works, and on the face of said disk are three or more projections, k k k, which are tapped for receiving screw-bolts j j j, that are used to secure a disk, G', corresponding in diameter to G, on the ends of said projections. The opposite faces of the two disks G G' should be parallel to each other, and their edges should be beveled, as represented in Fig. 1, for the purpose of receiving the beveled surfaces of a metallic ring-piston, J, which is introduced between the two connected plates in such manner that when the pump is in operation this beveled ring will alternately form and close a passage above or below said piston communicating with the hollow piston-rod F.

The ring J is constructed so as to work tightly within the cylinder A, and the disks G G', between which this ring works, should be sufficiently small to allow the water above and below them to rush between them and into the hollow piston-rod freely and unobstructedly at proper times.

The operation of my pump is as follows: As the piston rises the water flows in through the lower, front, or side chamber-passage, C, and fills the cylinder. As the piston descends the lower wing of the supply-valve E closes, as indicated in red lines, Fig. 1, opening the port of the upper passage, C', and allowing the water to flow in and fill said cylinder outside of the piston-rod. Simultaneously with the influx of water into the upper chamber-passage, C', the water that was first received into the cylinder A escapes between the lower plate, G', and ring J through the piston to the hollow rod F. As the piston again rises the water above it escapes through the space made between the piston or ring J and the upper disk, G, and rushes into the hollow rod F, as

before. Thus the operation continues, the water continually passing through the piston and being supplied alternately from above and below the same, keeping up a constant discharge through the pipe until the motion ceases.

It will be seen that the valves, by being connected to the piston in the manner described, do not obstruct the passage-way of the water to the hollow rod, their narrow or small legs *k k* affording a free passage to the hollow rod and obviating the obstruction which is offered by a central winged leg, as in other pumps of this particular character.

It will also be seen that the annular piston, by being beveled at top and bottom, in connection with the beveled disks or valves, enables me to secure a tight joint between the valves and the piston at such periods as may be necessary during the operation of the pump.

I am aware that a three-chambered cylinder is not new *per se* or in combination with a pump-piston. Therefore I do not claim such as my invention; but

What I do claim as my invention, and desire to secure by Letters Patent, is—

1. The arrangement consisting of the three-chambered cylinder or case, hollow piston-rod, double-acting piston, and double-acting oscillating supply-valve, substantially in the manner and for the purpose described.

2. Connecting the piston-valves directly to the hollow piston-rod by means of separated legs *k k*, substantially as described.

3. The doubled-beveled ring *J*, working between two beveled disks, *G G'*, applied to the piston-rod *F*, substantially as and for the purposes described.

4. The combination of the metallic wing-valve *E*, double-acting piston-valve, ring-piston, and hollow piston-rod with a three-chambered pump, substantially as described.

5. The detachable port-box *D*, valve *E*, and division *a*, in combination with side passages or ports, *C C'*, constructed substantially as and for the purposes described.

FRANCIS A. CHASE.
